United States Patent

Des. 238,584

Patented Jan. 27, 1976

238,584

PORTABLE TWO-WAY RADIO APPARATUS OR SIMILAR ARTICLE

Arnold S. Goldman, 149 Tennessee Ave. 33312, and
Donald K. Krumin, 5921 14th Terrace NE. 33316,
both of Fort Lauderdale, Fla.

Filed Mar. 26, 1975, Ser. No. 562,071

Term of patent 14 years

Int. Cl. D14—03

U.S. Cl. D26—14 K

FIG. 1 is a perspective view of the portable two-way radio apparatus or similar article showing the front, one side and the top of our new design;

FIG. 2 is an elevational view of the side of the portable two-way radio apparatus shown in FIG. 1;

FIG. 3 is an elevational view of the rear side of the portable two-way radio apparatus shown in FIG. 1; and

FIG. 4 is a plan view of the bottom side of the portable two-way radio apparatus shown in FIG. 1.

We claim:

The ornamental design for a portable two-way radio apparatus or similar article, substantially as shown.
